(57) **CLAIM**

The ornamental design for a chair, as shown and described.

DESCRIPTION

FIG. 1 is a perspective view from the front side of a chair.

FIG. 2 is a perspective view from the rear side thereof.

FIG. 3 is a front elevation view thereof.

FIG. 4 is a right side elevation view thereof. A left side elevation view is omitted because it is a mirror image to the right side elevation view.

FIG. 5 is a top plan view thereof.

FIG. 6 is a rear elevation view thereof.

FIG. 7 is a bottom plan view thereof; and,

FIG. 8 is a right side elevation view thereof when the seat is reclined.
